UNITED STATES PATENT OFFICE.

BRUNO E. JACOB, OF RIPPON, WISCONSIN.

DESIGN FOR A BADGE.

Application filed September 3, 1925. Serial No. 14,702. Term of patent 14 years.

To all whom it may concern:

Be it known that I, BRUNO E. JACOB, a citizen of the United States of America, residing at Ripon, in the county of Fond du Lac and State of Wisconsin, have invented a new, original, and ornamental Design for a Badge, of which the following is a specification, reference being had to the accompanying drawing, forming a part hereof.

In the drawing:

Fig. 2 is an edge view of the same.

I claim:

The ornamental design for a badge, as shown.

BRUNO E. JACOB. [L. S.]
